UNITED STATES PATENT OFFICE.

GEORGE J. HATZ, OF OMAHA, NEBRASKA, ASSIGNOR OF ONE-HALF TO CHARLES E. FULLER, OF OMAHA, NEBRASKA.

VALVE.

1,171,120.

Specification of Letters Patent.

Patented Feb. 8, 1916.

Application filed April 10, 1914. Serial No. 830,840.

To all whom it may concern:

Be it known that I, GEORGE J. HATZ, a citizen of the United States, and a resident of Omaha, county of Douglas, and State of Nebraska, have invented certain new and useful Improvements in Valves, of which the following is a full, clear, and exact description.

The invention relates to improvements in valves and more particularly to valves such as are employed for gage cocks and other valves that are adapted for use on and about steam boilers and locomotives.

The invention seeks to provide an efficient, inexpensive construction, in which a steam and water-tight joint is maintained between the valve stem and casing without employing the usual stuffing box.

A further object of the invention is to provide an improved construction in which the valve is moved longitudinally to and from its seat and is not rotated thereon, and in which the parts are so arranged as to maintain the valve seat clean.

The invention also seeks to provide improved means for conveniently oiling the parts of the valve to prevent them from "liming up."

With these and other objects in view, the invention consists in the features of improvement hereinafter set forth, illustrated in the preferred form in the accompanying drawings and more particularly pointed out in the appended claims.

Figure 1 is a central longitudinal section of a gage cock embodying the present improvements. Fig. 2 is a cross-section on the line 2—2 of Fig. 1. Fig. 3 is a view in elevation of the valve. Fig. 4 is a partial longitudinal section of the valve and valve seat showing a slight modification. Fig. 5 is a longitudinal central section of the globe valve embodying the present improvements. Fig. 6 is a plan view of the valve seat shown in Fig. 5.

The gage cock shown in Fig. 1 comprises a screw threaded shank or plug 1 that is adapted to be screwed into a correspondingly threaded opening in the boiler, the plug having a hexagonal flange 2 for receiving a suitable wrench. The plug or shank is provided with an externally threaded reduced end portion 3 which is adapted to engage the internally threaded end portion 4 of the chambered body 5 of the gage cock.

The part 4 of the chambered body is hexagonal to receive a suitable wrench and is adapted to be threaded on to the end of the plug into snug engagement with the flange 2 of the latter. A valve seat 6 is threaded into the outer end of the plug 1. This seat is tubular and the axial bore 7 extending therethrough communicates with the passage-way 8, extending through the plug or shank 1. At its end, the valve seat 6 is provided with an external, conical seating face 9 of very sharp taper, as shown.

On one side, the body portion or bonnet 5 of the gage cock is provided with a discharge nipple 10 and, at its end, it is provided with an integral extension 11 within which the valve 12 is guided. At its inner end, the valve 12 is provided with a short axial recess or chamber 13, so that an annular part 14 is provided which fits over and engages the external, conical surface 9 of the valve seat 6. If desired, the seat engaging portion of the valve may be provided with a lining 14' of babbitt, as shown in Fig. 4. The main body of the valve is square in outline, as most clearly shown in Fig. 2, and the bore of the extension or guide 12 of the valve casing of the body portion or bonnet is of corresponding shape, so that the valve is held against rotation. At the same time, it is free to shift longitudinally to and from the valve seat.

The extension or valve guide 12 of the casing is preferably provided with an integral end portion 15 having an opening 93 therein through which the valve stem 16 extends. The inner end portion 17 of the stem is screw threaded and engages an internally threaded bore formed in the main body of the valve 12. The outer end of the valve stem is provided with a squared portion 18 upon which fits a hand wheel 19, the latter being held in place by a nut 20 which is threaded upon the reduced end 21 of the valve stem. By rotating the valve stem, the valve, which is held against rotation, is shifted longitudinally to and from its seat.

The inner face of the end portion 15 of the extension or valve guide 12 is provided with a seat or recess for receiving a packing washer 22 of fiber, vulcanized rubber or the like, and the valve stem is provided with a fixed collar 23 which engages the inner face of the washer. A spring 24 is coiled about 110.

the valve stem and bears against the end of the valve casing and against the hub of the hand wheel 19. This spring presses the collar 23 of the valve stem against the washer 22 to thereby maintain a steam and watertight joint between the valve casing and stem. The spring also presses the hand wheel 19 against the nut 20 and prevents the loosening of the nut. Preferably, as shown, the hub of the hand wheel is provided with an inwardly extending, annular flange 25 which extends over and incloses the spring 24.

The improved construction shown can be cheaply manufactured. The plug, body portion or bonnet and the handle may be formed of cast iron and preferably of malleable cast iron. The valve and valve seat are preferably formed of brass. The valve and also the valve seat can be conveniently removed and renewed. Inasmuch as the valve is provided with a square shank or body portion which fits into a correspondingly shaped bore of the extension or guide 12, the valve is held against turning and has a straight, longitudinal movement to and from the seat. In this way, the valve cannot twist on or cut the seat. The external conical seating surface 9 of the valve seat has a very sharp taper, as shown, so that the slight longitudinal movement of the annular valve on this seating surface prevents scale from forming thereon, and at all times maintains the seat clean, so that the valve can be securely closed. Moreover, if the valve is closed when the parts are hot, the valve will shrink onto its seat as it is cooled, and will not shrink away from its seat and leak, as in prior constructions.

The spring 24 is held under considerable tension, so that the packing washer 22 is compressed to form a secure steam and water tight joint about the valve stem, and the spring also serves to develop sufficient friction between the hand wheel and the nut 20 to prevent the loosening of the latter. Preferably on its upper side, the valve stem guide is provided with a nipple 26 within which is threaded a plug 27. A knurled disk or cap-piece 28 is provided on the outer end of the plug with a seating face 29 which engages the outer end of the nipple 26 to form a tight joint therewith. By removing the cap or disk 28 of the plug 27, the interior moving parts of the valve may be oiled. This is an important feature, particularly if water is employed that contains lime or other like salts. Under such circumstances, scale is deposited on parts of the gage cock and corrosion occurs. In the present construction, the parts of the gage cock may be conveniently oiled without disassembling them, so that "liming up" and corroding is prevented.

Fig. 5 illustrates a globe valve with the

present improvement applied thereto. The casing 30 may be of any suitable form. That shown is similar to the casing of an ordinary globe valve and is provided at its ends, as usual, with internally threaded hexagonal flanges 31. The partition 32 is provided with an internally threaded port or opening extending therethrough, and the valve seat 33 is removably threaded therein. As in the form shown in Fig. 1, the seat is provided with an external, conical bearing face 34 of sharp taper, and which is preferably provided at its inner end with a shoulder 35 that abuts against the face of the partition 32. Preferably, also, as shown, the valve seat is provided with internal lugs 36, as shown most plainly in Fig. 6, which are adapted to receive a suitable tool so that the valve seat can be conveniently removed for repairs or the like.

Above the valve seat the casing is provided with an internally threaded portion 37 within which the lower end of the bonnet 38 is screwed. The latter is provided with a hexagonal portion 39 for receiving a suitable wrench and with a flange 40 which is adapted to abut against the portion 37 of the valve casing. The valve 41 comprises an enlarged annular portion upon the inner or lower end of a shank 42. The annular or cup-shaped valve 42 surrounds the valve seat and is provided with a conical face of sharp taper which cooperates with the tapered bearing face 34 of the valve seat 33. This construction prevents scale from lodging on the seat and effectually prevents leaking of the valve when the parts are cooled.

The shank 42 of the valve, like that previously described, is square in cross-section and fits within the correspondingly shaped bore 43 of the extension or guiding portion 44 of the bonnet. Like the form previously described, the bonnet is provided with an integral end 45 having an opening for the valve stem and a seat on its inner face with a packing washer. The construction and arrangement of the valve stem, packing therefor and hand wheel, and also of the oiling device, are similar to those already described in connection with the form of the invention shown in Fig. 1. It should be noted that the construction obviates the necessity of employing a separate cap on the end of the guiding portion 44 of the valve casing or bonnet. The packing and valve stem are inserted from within the bonnet and are held in place by the exteriorly arranged hand wheel 19 and spring 24.

It should be noted that in both forms means is provided for effectually forming a steam tight joint between the valve stem and casing without employing a stuffing box. Moreover, the valve stem does not reciprocate through the packing, so that it does

not become worn, as in prior constructions, and will not leak. Ordinarily, the valve is held against rotation on the valve seat, so that it cannot cut the latter, but, if it is desired to grind the valve on its seat, the bonnet of the valve casing may be disconnected, and the valve run down into engagement with the seat. Then by rotating the valve back and forth, it can be ground on its seat.

10 In the construction shown in Fig. 5, the portion 37 of the valve casing affords a large opening, so that when the bonnet is removed, ample access is afforded to the valve seat 33, so that the latter can be readily removed. In this form, also, the valve projects beyond its bonnet when the latter is removed, so that it can be readily ground.

20 It is obvious that numerous changes may be made in the details set forth without departure from the essentials of the invention as defined in the claims.

I claim as my invention:—

25 1. The combination with a plug exteriorly threaded at its inner and outer ends and provided at its outer end with a projecting valve seat, of a valve casing formed of a single piece threaded at its inner end to en-
30 gage the outer end of said plug, the outer end portion of said casing being formed with a non-circular chamber to receive a valve and having between said non-circular chamber and its inner end an expanded
35 chamber around the end of the valve seat, said expanded chamber being provided with a discharge nipple, said casing being pro-
40 vided at its outer end, beyond said non-circular chamber, with a contracted opening and with an interior recess adjacent said contracted opening to receive a washer, a

washer within said interior recess, a valve 45 slidably and non-rotatably mounted within said non-circular chamber of the casing and provided at its outer end with an interiorly threaded part, a valve stem having a threaded inner end to engage said valve and having a collar adjacent its threaded inner end to engage said washer, and means connected to the outer end of said valve stem whereby 50 it may be rotated to effect the sliding movement of the valve; said valve being removably held within the valve casing until said casing is bodily detached from said plug.

2. The combination with a valve casing 55 having a contracted opening for the passage of the valve stem, said casing having its interior provided with an annular recess adjacent said contracted opening, said casing having its interior formed with a non-circular chamber to receive the shank of the valve and with a chamber for oil between the outer end of said non-circular chamber and said annular recess, a valve mounted 60 to slide within said non-circular chamber of the casing, a valve stem having its inner end threaded to engage a correspondingly threaded outer portion of said valve and having a collar arranged within said annular recess, a washer arranged around the 65 valve stem within said recess and adjacent said collar and means mounted upon the outer end of said valve stem for turning the same, the outer portion of said casing being provided with a passage leading to 70 said oil chamber and a cap for closing said passage.
